(57) **CLAIM**

The ornamental design of a listening and viewing station, as shown and described.

DESCRIPTION

FIG. 1 is a front perspective view of the invention, it being understood that the broken lines are for illustration purposes only and form no part of the claimed design; and,

FIG. 2 is a back perspective view thereof, it being understood that the broken lines are for illustration purposes only and form no part of the claimed design.

1 Claim, 2 Drawing Sheets

FIG. 1

FIG. 2
